UNITED STATES PATENT OFFICE

CLIFFORD OLDER, OF WILMETTE, ILLINOIS

EXPANSION JOINT FOR PAVEMENTS AND THE LIKE

Application filed May 24, 1929. Serial No. 365,681.

The present invention relates to concrete floors, pavements, sidewalks and the like, and is particularly concerned with expansion joints for such concrete structures.

The concrete pavements of the prior art are ordinarily constructed in a plurality of sections with cracks between the sections, and substantially larger expansion cracks located at regular intervals for the purpose of permitting the longitudinal expansion of the pavement under changes of temperature of the pavement. When the separate sections of the pavement expand, there is a gradual sliding of the sections toward the expansion crack or joint, but when the sections subsequently contract, they do not tend to return to their former position, with the result that the relatively wide expansion crack soon disappears and is divided among the plurality of cracks formed between the adjacent sections of the pavement, and it is practically impossible to prevent this action of the pavement sections in closing up the expansion joint.

The open expansion joints and cracks between adjacent sections soon become filled with dust, soil, floor sweepings or sand particles, and as this material is generally incompressible it follows that when expansion again takes place, the joints cannot close between the adjacent sections and the whole series of sections is pushed still further toward the expansion joint until eventually all of the joints, including the expansion joint, become filled with hard packed unyielding material. The purpose of the expansion joint is then defeated and further expansion of the concrete sets up compression stresses as great as would be the case had no expansion joint been provided in the first place.

One of the objects of the present invention is the elimination of the foregoing difficulties and others, by the provision of an improved expansion joint of relatively simple and economical construction, which is adapted to permit relative movement between adjacent sections of the pavement, and to prevent the filling of the cracks between the sections with dirt or other foreign material.

Another object of the invention is the provision of an improved expansion joint assembly, including a simplified form of expandible member having a substantially V-shaped expandible portion and having anchoring flanges for securing the same in the adjacent pavement sections.

Another object is the provision of an improved expansion joint including an improved expandible member of simple and economical construction, a division member for supporting said expandible member and for insuring the formation of separate sections of pavement, and aligning means carried by said division member for maintaining the separate sections of pavement in the same plane, while permitting expansion or contraction of the separate sections under changes of temperature.

Other objects and advantages of the invention will be apparent from the following description and from the accompanying drawings, in which similar characters of reference indicate similar parts throughout the several views.

Referring to the drawings, of which there are two sheets;

Fig. 1 is a vertical sectional view of a portion of a concrete pavement, floor, sidewalk or the like, which is equipped with an expansion joint of the simplest type constructed according to the present invention;

Fig. 2 is a similar view of the expansion joint after the adjacent sections of the pavement have contracted, showing the parts in different position;

Fig. 3 is a similar view of a modified form of construction, including a division plate for supporting the expandible member;

Fig. 4 is a view in perspective of a portion of the division plate of Fig. 3;

Fig. 5 is a view similar to Fig. 3 of a modified form of construction, having a division plate with aligning formations and an expandible member adapted to be supported upon the division plate;

Fig. 6 is a similar sectional view of a modified form of construction, including a division plate with an aligning plate and special

means of support for the division plate during the construction of the pavement;

Fig. 7 is a vertical sectional view taken on the plane of the line 7—7 of Fig. 8;

5 Fig. 8 is a view similar to Fig. 6, showing the expansion joint after the pavement sections have contracted with the parts in a different position;

10 Fig. 9 is a sectional view of a modified form of construction in which the pavement crack is protected above and below;

Fig. 10 is a side elevation of the parting strip and supports shown in Fig. 9 apart from the pavement.

15 While the embodiment chosen to illustrate the invention is a concrete pavement, it should be understood that the present invention is applicable to practically all forms of pavement or other monolithic construction in

20 which it is desirable to provide an expansion joint between members which are cast or molded in place, for the purpose of preventing the filling of the cracks with foreign material.

25 Referring to Fig. 1, 10 and 11 indicate the adjacent portions of concrete sections of a pavement, and in this embodiment the sections may be provided with a crack 12 naturally formed as the result of stresses when 30 the adjacent sections contract, or formed by means of a trowel or other tool when the sections are laid. The expansible member 13 comprises a strip of non-corrosive sheet metal which is formed with an expansible central 35 portion 14 and integral anchoring flanges 15 and 16 on each side of the expansible portion 14.

In order to provide an expansible member 40 of relatively low cost and economical construction, the expansible portion 14 preferably comprises a substantially V-shaped bend in the strip 13, extending longitudinally of the strip and preferably provided with a curve 17 at the bottom of the V to facilitate bending without breaking of the metal. The upwardly extending diverging flanges 18 and 19 of the V-shaped member 14 are joined to downwardly extending flanges 20 and 21 adapted to extend into the adjacent sections 45 10 and 11 of concrete, and the downwardly extending flanges 20 and 21 are provided with anchoring formations 15 and 16 for securely anchoring the expansible member 13 in each of the concrete sections 10 and 11.

55 It will be evident that the anchoring formations 15 and 16 may take any of a plurality of different forms, but in the preferred embodiment, the anchoring formations 15 and 16 comprise horizontally extending 60 flanges 15 and 16 with backwardly turned edges 22 and 23 for engaging in the concrete and preventing the withdrawal of the expansible member 13. The horizontally extending flanges 15 and 16 provide a substantial area of support for the expansible mem-

ber 13 after it has been pressed into the green concrete pavement, so that the expansible member 13 will not settle substantially after the concrete has been finished and before it has taken its set.

70 The upper adjacent corners 24 and 25 of the concrete sections 10 and 11 are preferably rounded off to a surface substantially flush with the inner surface of the diverging flanges 18 and 19 to prevent injury to 75 the corners of the sections by traffic, and to provide a finished appearance at the expansion joint. The concrete may extend upwardly between the flanges 20 and 21 of the expansible member 13, without interfering 80 with the functions of the expansible member, thereby providing additional support for the expansible member during the construction of the pavement.

85 The operation of the expansible joint is as follows.

When the concrete has set and a change of temperature causes contraction of the adjacent sections 10 and 11, the crack 12 between these sections will be widened as shown in 90 Fig. 2, and the V-shaped expansible member 14 will be moved upward to the position shown in Fig. 2, flexing at the bend 17 and at the juncture between the flanges 18 and 20 and flanges 19 and 21, respectively.

95 The dirt or other foreign matter indicated at 26 will be prevented from entering the crack 12 and when the sections 10 and 11 expand again, the crack will be open to permit expansion of the pavement without producing compression stresses.

100 Referring to Fig. 3, the expansion joint illustrated in this figure includes an expansible member 13 of substantially the same form as that previously described, together 105 with a division plate 27 for producing a definite line of division between the adjacent pavement sections 10 and 11, and for supporting the expansible member in place during the formation of the pavement. A short 110 section of the division plate 27 is shown in perspective in Fig. 4 and the division plate 27 comprises a strip of sheet metal which is provided with a plurality of transverse slots 28 forming tongues 29, 30 of metal 115 which may be bent in opposite directions to form a support substantially complementary to the lower surface of the V-shaped expansible member 13. The tongues 29, 30 do not interfere with the operation of the expansible member 13 since the expansible member 13 is adapted to flex upward during contraction of the concrete, and it is contemplated that expansion cracks may be provided at other points in the concrete for permitting further expansion of the concrete sections. Such expansion cracks may be formed substantially as shown in Fig. 2, with an expansible member 13 covering the upper portion of the crack.

Referring to Fig. 5, the division plate 31 illustrated in this embodiment comprises a strip of sheet metal which is formed with a longitudinally extending rib 32 of substantial width having oblique side flanges 33 and 34. The division plate 31 forms a metal lined recess 36 in the pavement section 10 and a protuberance 35 extending along one edge of the pavement section 11, and adapted to engage within the recess 36 to maintain the alignment of the pavement sections 10 and 11, or to prevent settling of one section relative to the other. The expandible member 13 of this embodiment is of substantially the same form as that previously described, except the V-shaped expandible portion 14 is provided with an inwardly projecting, longitudinally extending integral rib 37 forming a groove 38 in the lower side of the expandible member 13 for receiving the upper edge of the division plate 31. The rib 37 of the expandible member 13 may slide upward on the division plate 31 when the pavement sections 10 and 11 contract under temperature changes.

Referring to Figs. 6 to 8, the expandible member 13 illustrated in this embodiment is substantially the same as that disclosed in Figs. 1 to 3. The division plate 39 comprises a sheet metal member having its upper portion formed substantially as shown in Fig. 4. Since the foregoing details are the same as the previous embodiments, they need not be described further.

The division plate 39 of this modified form of expansion joint is preferably provided with a longitudinally extending rib 40 comprising side flanges 41 and 42 of substantial width joined by the end flange 43. The longitudinally extending rib 40 forms a groove 44 which is adapted to receive an aligning member 45 comprising a metal plate slidably supported in the groove 44 and the plate 45 is of sufficient length to project out of the groove 44 into the adjacent concrete section 10.

The division plate 39 is provided with the downwardly extending supporting flange 46 and the flange 46 may be supported in a plurality of driven members such as stakes or pegs 47, having slots 48 to receive the division plate 39. The division plate 39 thus forms a metal lined slot 44, the side walls of which are not tapered, so that the slot is in continuous slidable engagement with the aligning member or plate 45, and when the adjacent concrete sections 10 and 11 contract as shown in Fig. 8, the plate may slide in the groove 44 or the division plate 39 may slide in its groove in the section 11.

It is, of course, understood that any of the expansion joints described herein may be used for either transverse joints in pavement or longitudinal joints, and the expandible member 13 is adapted to be used for main-

taining the alignment of the adjacent sections 10 and 11 under certain conditions.

The present invention is applicable to joints in which the pavement sections are initially spaced from each other and therefore adapted to permit expansion of the sections, or joints in which the pavement sections are initially joined or in contact so that the joint is intended to permit contraction of the sections. Since either of these types of joints will permit either expansion or contraction at certain temperatures, I employ the term "expansion joint" generically in the present specification and claims to include a structure performing either or both of these functions.

It will thus be observed that I have invented an expandible joint for concrete pavement and the like, which is adapted to prevent the filling up of expansion cracks or other cracks between adjacent sections of concrete; and the present expansion joint includes a sheet metal expandible member of relatively simple construction so that it may be economically manufactured.

One of the important features of the present invention is the elimination of the parts of the prior complicated structures and the performance of their function by a simplified structure which is sturdy and economical, without substantially increasing the cost.

Referring to Figs. 6, 7 and 8, the division plate illustrated in these modified forms is peculiarly adapted to effect a more perfect alignment of the concrete sections than is possible where the interlocking portions of the concrete sections 10 and 11 are tapered as shown at 33 in Fig. 5.

The aligning member 45 preferably comprises a steel plate having substantially parallel upper and lower surfaces so that the plate may slidably engage the adjacent walls of the recess formed in one or both of the concrete sections 10 and 11. Where the aligning member is tapered, the space between the aligning plate or projection and its complementary recess, increases in width as the sections contract, and consequently the tapered aligning members do not perform the function of alignment and support as the crack between the sections widens.

Where the aligning member is provided with substantially parallel guiding surfaces such as those of the steel plate 45, the aligning member slidably engages in the concrete sections at all times, and positively prevents any settling or vertical movement of one section relative to the other. It is, of course, possible to provide aligning members 45 which have other shapes than the simple flat plate illustrated, provided such aligning members have substantially parallel guiding surfaces, but the simple flat plate has additional advantages in that it may be most eco-

nominally constructed from ordinary steel stock.

Referring to Figs. 9 and 10, in this modified joint construction, the crack 12 is protected by an expandible member 14 carried by the pavement sections 10 and 11 adjacent the top of the pavement, and by a second expandible member 14 carried by the pavement sections adjacent the bottom of the pavement, thereby positively preventing foreign matter from entering the crack from either direction.

It should be understood that in each of the foregoing embodiments, expandible members may be used on either or both top or bottom of the pavement.

In the present embodiment, the expandible members 14 may be provided with downwardly and inwardly turned anchoring flanges 50 forming a groove 51 which is adapted to receive a horizontally extending flange 52 carried by the parting strip 53. The parting strip 53 has a central portion similar to the parting strip of Figs. 6 to 8, being formed with a longitudinally extending rib 40 forming a groove 42 adapted to receive the aligning member 43.

The lower edge of the parting strip 53 is provided with a similar horizontally extending flange 52 for engaging the expandible member 14 and in some embodiments of the invention, the flanges 52 may be spot welded, riveted or otherwise permanently secured to the adjacent flanges of the expandible members 14.

The combined parting strip, aligning member, and expandible members may then be supported in place by a plurality of supporting members 54 comprising sticks or pins similar to the sticks 47, but having slots 55 of a shape and a size sufficient to receive the parting strip and aligning member and support them upon the shoulders 56.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States, is:

1. A pavement or the like comprising a pair of sections having adjacent edges, and means for connecting said sections and preventing filling of a crack between said edges, comprising a flexible sheet metal member having a substantially V-shaped bend extending longitudinally of said crack, and integral anchoring flanges extending into said pavement sections and formed on each side of said V-shaped bend, said pavement sections having their adjacent upper corners formed with

surfaces substantially flush with the upper surface of said metal member.

2. A pavement or the like comprising a pair of sections having adjacent edges, and means for connecting said sections and preventing filling of a crack between said edges, comprising a flexible sheet metal member having a substantially V-shaped bend extending longitudinally of said crack, and integral anchoring flanges extending into said pavement sections and formed on each side of said V-shaped bend, and a division plate comprising a sheet metal member having oppositely extending tongues formed along its upper edge to provide a support for said flexible metal member. 70 75 80

3. A pavement or the like comprising a pair of sections having adjacent edges, and means for connecting said sections and preventing filling of a crack between said edges, comprising a flexible sheet metal member having a substantially V-shaped bend extending longitudinally of said crack, and integral anchoring flanges extending into said pavement sections and formed on each side of said V-shaped bend, a division plate comprising a sheet metal member having oppositely extending tongues formed along its upper edge to provide a support for said flexible metal member, and a plurality of driven members having slots for receiving said division plate to support said division plate. 85 90 95

4. A pavement or the like comprising a pair of sections having adjacent edges, and means for connecting said sections and preventing filling of a crack between said edges, comprising a flexible sheet metal member having a substantially V-shaped bend extending longitudinally of said crack, and integral anchoring flanges extending into said pavement sections and formed on each side of said V-shaped bend, a division plate comprising a sheet metal member having oppositely extending tongues formed along its upper edge to provide a support for said flexible metal member, said division plate having a longitudinally extending rib forming a slot substantially parallel to the pavement and means for aligning said sections, slidably mounted in said slot. 100 105 110 115

5. An expansion joint assembly for concrete pavements or the like comprising a flexible sheet metal member having a V-shaped groove formed longitudinally of said member, downwardly extending flanges on each side of said groove, anchoring flanges carried by said downwardly extending flanges, a division plate having oppositely bent tongues along one edge for engaging the sides of said V-shaped groove, said division plate having a longitudinally extending rib forming a slot, and an aligning plate slidably mounted in said slot. 120 125

6. A pavement or the like comprising a pair of sections with adjacent spaced edges 120

- forming an open expansion crack between said edges, an expansible member located adjacent one of the faces of said sections to close said crack at substantially the face and prevent ingress of foreign material to said crack, said expansible member comprising an integral sheet metal member, formed with a central longitudinally extending, laterally expansible portion, and with laterally projecting anchoring flanges, extending into the body of said sections and secured therein, and a division plate for producing the expansion crack between said sections a predetermined point in substantial alignment with the expansible portion of said member, said division plate having a plurality of oppositely bent flanges at its upper edge for engaging on opposite sides of the expansible portion of said expansible member.
- 10 7. A pavement or the like comprising a pair of sections with adjacent spaced edges forming an open expansion crack between said edges, an expansible member located adjacent one of the faces of said sections to close said crack at substantially the face and prevent ingress of foreign material to said crack, said expansible member comprising an integral sheet metal member, formed with a central longitudinally extending, laterally ex-
- 25 pansible portion, and with laterally projecting anchoring flanges, extending into the body of said sections and secured therein, and a division plate for producing the expansion crack between said sections a predetermined point in substantial alignment with the expansible portion of said member, said division plate comprising a flat sheet metal member having slits in its upper edge and having the flanges between said slits bent alternately
- 30 35 40 in opposite directions to form a supporting surface for said expansible member.

In witness whereof, I hereunto subscribe my name this 11th day of May, 1929.

CLIFFORD OLDER.
